UNITED STATES PATENT OFFICE.

LUCIUS A. LE MIEUX, OF SEYMORE, WISCONSIN.

STEAM-ENGINE GOVERNOR.

SPECIFICATION forming part of Letters Patent No. 530,538, dated December 11, 1894.

Application filed March 28, 1892. Serial No. 426,758. (No model.)

To all whom it may concern:

Be it known that I, LUCIUS A. LE MIEUX, a citizen of the United States, and a resident of Seymour, in the county of Outagamie, and in the State of Wisconsin, have invented certain new and useful Improvements in Steam-Engine Governors and Reversing Mechanism; and I do hereby declare that the following is a full, clear, and exact description thereof.

10 My invention relates to new and useful improvements in steam engine governors, and relates more particularly to a governor for engines employing a rotary valve for controlling the supply of steam to the cylinder and the exhaust of steam therefrom.

15 The object of my invention is to provide a governor for steam engines of this class which shall be automatic in its operation, the arrangement of the governor mechanism being such that by an excessive speed of the engine, it will be operated so as to advance the rotary valve into a position to cause it to cut off steam at an earlier portion of the stroke of the engine so as to cause the engine to work 20 expansively.

25 The several features of my invention will be hereinafter more fully described with reference to the accompanying drawings, and pointed out in the appended claims.

30 In the drawings:—Figure 1. is a vertical sectional view of an engine embodying my invention, said section being taken at right angles to the axis of the cylinder. Fig. 2. is a plan view of the governor mechanism. Fig. 3. is a detail cross section taken on line 3—3 of Fig. 2, and shows the reversing mechanism. Fig. 4. is a detail elevation of one of the parts of the governor mechanism. Fig. 5. is a longitudinal vertical section of the device taken 35 on line 5—5 of Fig. 1. Fig. 6. is an enlarged view of a portion of the governor mechanism.

In said drawings:—A represents the cylinder, B the piston, and C the piston rod of the engine.

40 D represents a cylindric steam chest having a steam inlet port D', ports d d leading to opposite ends of the cylinder A, and an exhaust port E. The steam chest is preferably formed from a cylindric casing or shell F in 45 which the ports are formed as illustrated in the drawings, and said casing is conveniently arranged within a cylindric opening in the

casting forming the engine frame, but the valve may be arranged to engage directly with the inner surface of a cylindric chamber 55 formed in said casting and provided with the necessary ports, the casing or shell being in this case dispensed with, if desired.

A valve frame G is revolvably engaged within the cylindric steam chest D as shown in Figs. 60 1 and 5, said frame being provided with circular end portions G' G' of a diameter corresponding with the diameter of the said cylindric steam chest, and arranged to fit closely within the ends of the same. Parallel side 65 pieces or plates G² G² are arranged to extend longitudinally between the end portions G' G', and between these plates the operating portions of the valve are secured.

The operating portion of the valve comprises 70 two valve plates g g, of substantially T shape, and having their shanks engaged between the side pieces of the valve casing or frame, and springs g' g' are arranged within said frame in such a manner as to press 75 said plates outwardly against the walls of the steam chest.

A spindle H extends from one end of the valve frame and passes through a stuffing box or gland h in the end of the cylindric 80 steam chest, and is provided at its outer end with a collar or sleeve H' which is made fast to it and provided with oblique or substantially V shaped slots h' in one or more of its sides, as illustrated in Fig. 4. As many of 85 these slots may be employed as may be desired, two being the preferred number.

A wheel I, driven from another wheel I' which is operatively connected with the moving parts of the engine by means of a crank 90 I², is loosely mounted upon the outer end of the spindle II, the hub J of said wheel being provided with a tubular projection J' arranged to surround the collar or sleeve H' on the end of said spindle and provided with longitudinal slots j j. Angular arms j' j' are provided upon the outer end of the tubular portion of said hub, and between these arms are pivotally engaged bell crank arms K K carrying at their extremities, weights k k, 95 and having their inner ends k' engaged with suitable links k² k². A collar L is movably engaged with the outer surface of the tubular portion of the hub and is provided with ears 100

ll to which the links *k² k³* are pivotally engaged, and is also provided with pins *L'* and *L²* projecting inwardly from its inner periphery and engaged with the slots *j j* in the outer 5 end of the hub *J*. One or both of these pins are prolonged sufficiently to engage with the oblique or **V** shaped slot or slots *h'* in the sleeve *H'* as is illustrated in Figs. 1, and 3. The collar *L* is further provided with a peripheral groove *l'*, and a lever *M* is pivotally engaged with the frame of the engine as at 10 *m*, and is bifurcated at one end and the furcations are arranged to embrace the outside of the said collar and each provided with an inwardly extending pin *m'*, engaging with the groove *l'*. A handle *M'* is provided at the other end of the lever *M*, and a pawl *M²* is pivoted to said handle and is arranged to engage with an arc *N* on the engine frame. An 15 operating handle *m²* is provided on the pawl *M²* and is arranged to be grasped by the hand at the same time as the handle *M'* of the lever *M*, and a shoulder *n* is arranged on the arc *N* so as to limit the movement of the lever *M*, 20 by engaging with the pawl *M²* in an obvious manner.

The operation of my improved governor mechanism is as follows: The reciprocating motion of the piston with the connected parts 25 communicates a rotary motion to the wheels *I'* and *I*, which latter wheel will rotate the bell crank arms *K K* which carry the governor balls *k k*. A rotation of said arms will obviously cause the balls at their outer ends to 30 spread apart, (this movement being resisted by a spring *K'* which is connected with said arms,) the ends *k' k'* of the said bell crank arms being thereby oscillated about the pivotal connections with the arms *j' j'*, so as to 35 draw the links *k² k³* and the collar *L* toward the outer end of the spindle *H* in an obvious manner.

By the engagement of the pin or pins on the collar *L* with the **V** shaped slot or slots 40 *h'* in the sleeve *H'*, an outward movement of said collar will obviously cause said pin or pins to move outwardly in engagement with the branches of said slots, so as to rotate the sleeve within the tubular portion *J'* of the 45 hub *J*, thus rotating the spindle *H* and with it the valve *G* into a different position relative to the wheel *I*. This movement of the valve will advance it so as to cut off steam at an earlier portion of the stroke of the engine, 50 such advancement of the valve being obviously in proportion to the spread of the governor balls and rotation of sleeve *H'*. In this manner, the engine will be caused to work expansively with a corresponding economy 55 of steam.

An increase in the load on the engine will 60 obviously operate to retard the engine and the balls *k k* will approach each other, thereby operating through the medium of the bell 65 crank levers *K K* to produce an inward movement of the collar *L*, and moving the valve

toward its initial position so as to take steam earlier in the stroke.

When the engine is idle, the spring *K'* will 70 operate to move the outer ends of the bell crank arms *K K* toward each other and to move the collar *L* into a position to bring the pin or pins thereon toward the inner ends of the **V** shaped slots *h'*, the limit of this inward movement being at a point some distance 75 from the inner ends of said slots, so that when steam is turned on to start the engine, said pin *L'* will move outwardly in the branch of the **V** shaped slot with which it was previously engaged, and the engine 80 will run as before. If now, the engineer desires to reverse the engine, he grasps the lever *M* by the handle *M'*, compresses the handle of the pawl *M²* so as to hold it out of the line of the shoulder *n* on the arc *N*, and moves 85 said lever so as to carry the collar *L* outwardly upon the tubular portion of the hub *J*, until the pin *L'* is carried out of engagement with the **V** shaped slot *h'*, the slots *j j* being made of sufficient length to permit of this movement 90 of the collar. When the pin is out of engagement with the slot *h'*, the valve will cease to move, and steam will carry the piston to the end of its stroke, at the same time, moving the wheel *I* and collar *L* into a position 95 to enable the pin *L'* to engage with the other branch of the slot *h'*. This movement of the parts will obviously serve to change the relative positions of the moving portions of the engine and the rotary valve, so as to reverse 100 the motion of the engine.

In the ordinary operation of the engine, the outward movement of the governor balls *k k*, and the consequent movement of the collar *L* and lever *M*, will be limited by the engagement of the pawl *M²* with the shoulder *n* on the arc *N*, so as to prevent the pin *L'* from moving out of engagement with the **V** shaped slot *h'*, while the reverse motion of the said parts will be limited by the stop *n'* on the other end of the arc *N*. It will be thus seen that the operation of the engine is perfectly regulated, the supply of steam to the cylinder being proportionate to the amount of load and consequent demand upon the engine.

I would have it understood that I do not desire to limit myself to the exact form of construction and arrangement illustrated in the drawings and herein described as various modifications may be made in the details of construction without departure from my invention.

Having thus described my invention, what I claim as new, and desire to secure by Letters Patent of the United States, is—

1. The combination in a steam engine, of a rotary valve for controlling the admission of steam to and the exhaust of steam from the cylinder, a spindle extending from the end of said rotary valve and provided at its outer end with an oblique slot, a wheel loosely mounted on said spindle and carrying governor mech-

anism, and a pin secured to said governor mechanism and operatively engaged with said oblique slot in said spindle, substantially as described.

5 2. The combination in an engine, of a rotary valve for controlling the admission of steam to and the exhaust of steam from the cylinder, a spindle extending from one end of said rotary valve and provided at its outer 10 end with a substantially V shaped slot, a wheel loosely mounted on said spindle and operatively connected with a moving portion of the engine, and provided with a tubular extension upon one end of its hub to which extension is secured suitable governor mechanism, a collar movably engaged with the outside of said extension and operatively engaged with the said governor mechanism so as to be adjusted longitudinally upon said extension by the movements of said governor mechanism, and a pin carried by said collar and adapted for engagement with the V shaped slot in the outer end of the spindle, substantially as and for the purposes de- 15 20 25

3. The combination in a steam engine, of a rotary valve, for governing the admission and exhaust of steam a spindle projecting axially from one end of said valve and provided at its outer end with a substantially V shaped slot, a collar located around the outer end of said stem and provided with one or more inwardly projecting pins adapted for movable engagement with the oblique branches of said slot, said collar being operatively engaged with governor mechanism, a vibrating lever operatively engaged with said collar, stops for limiting the movement of said lever, and means for freeing said lever to permit it to be moved so as to carry the said pins out of engagement with said slot, substantially as and for the purpose described.

In testimony that I claim the foregoing I have hereunto set my hand, at Seymour, in the county of Outagamie and State of Wisconsin, in the presence of two witnesses.

LUCIUS A. LE MIEUX.
